UNITED STATES PATENT OFFICE

HOWARD W. LINKERT, OF INDIANAPOLIS, INDIANA, ASSIGNOR TO THE WHEELER-SCHEBLER CARBURETOR CO., OF INDIANAPOLIS, INDIANA, A CORPORATION OF INDIANA

CARBURETOR

Application filed March 14, 1925. Serial No. 15,468.

In the operation of liquid-fuel carburetors and their associated engines, one of the conditions which tends to interfere with proper operation is the introduction into the engine 5 of too rich a mixture at the beginning of idling, following a period of operation under low suction, especially when such low suction is accompanied by low air velocity. This frequently results in a stopping of the engine, 10 generally known as "dying" or "stalling".

When a carburetor using liquid fuel is operating under low suction and low air velocity, the liquid fuel collects in considerable quantity on the various surfaces within 15 the passage for explosive mixture, as on the manifold walls and on the carburetor-throttle disk and shaft. When the suction is suddenly raised, as upon closing the throttle from wide-open position to idling 20 position, this collected fuel is added to the normal idling mixture; which makes the mixture so rich that it will not ignite, and so causes the engine to stop.

Moreover, with many carburetors it is difficult 25 to start a motor, especially when the motor is hot, when the throttle is closed; because of an insufficient quantity of mixture, or because the mixture is too rich from fuel which has remained in the intake passages 30 from the previous operation, or both. The attempts to start motors with closed throttles have therefore caused much trouble, with heavy drain on the battery supplying the 35 starter.

It is the object of my present invention to 40 avoid these difficulties. The primary object is to lessen the danger of having the motor stop upon the closing of the throttle to idling position. A secondary object is to facilitate

starting, especially with a hot motor. More specifically, it is the object of my invention to provide an increased supply of air in the mixture that reaches the engine in the early part of a period of idling; and, 45 secondarily, to ensure a larger supply of explosive mixture to the engine during starting.

In carrying out my invention, I provide means for admitting an additional supply of air, (desirably by admitting explosive mixture, which contains air, from the mixing

chamber,) to the mixture-discharge passage between the throttle and the engine for a period at the beginning of idling and during starting, and for cutting off this additional supply after a predetermined time after the initiation of a high-suction condition above the throttle.

In the preferred form of my invention, I provide a by-pass passage or conduit around the throttle, which by-pass passage or conduit operates to permit explosive mixture to pass around the throttle when the latter is closed; and I provide for this by-pass or conduit an automatically operated control valve which operates to close such passage or conduit after a predetermined time following the beginning of a high-suction condition above the throttle.

The details of this will appear herein-after.

The accompanying drawing illustrates my invention: Fig. 1 is a fragmentary vertical section through a carburetor embodying my invention in its preferred form, only part of the carburetor being shown; and Fig. 2 is a similar fragmental view, showing a detail of a modification.

My invention is applicable to carburetors of any design; but is of especial value in connection with the carburetor invented by Otto Carter Berry and myself, shown in our co-pending application Serial No. 639,131, filed May 15, 1923, so that I have used that carburetor to illustrate my invention. In that carburetor, as in others, it is important to prevent too great enrichment of the mixture which reaches the engine upon the closing of the throttle, such as tends to occur by the adding to the idling mixture leaving the carburetor of fuel which has collected on the manifold walls and the throttle disk and shaft during an immediately preceding period of operation under low suction and low velocity.

In the carburetor shown, fuel 10 in a float bowl 11 is supplied to a fuel nozzle 12, which discharges within a venturi 13; which receives primary air through a primary-air inlet opening 14, and projects upward into and discharges within a mixing chamber 15. This

mixing chamber also receives secondary air from a secondary-air supply passage 16, with the detail of which this invention is not concerned. The outlet of the mixing chamber is controlled by a throttle 17, shown as of the usual butterfly or disk type mounted on a shaft 18 operated by an arm 19. The details of the carburetor so far described and used may be varied as desired, and are not essential to my invention.

Above the throttle 17 a hole 20 opens into the main passage. The effective size of this hole 20 may be controlled by a screw-plug 21, which is screw-mounted in the outer end of such hole to close it, and has a stem extending along the hole for a considerable distance. A number of such plugs are provided, with different diameters of stem, so that by the use of the proper plug any desired effective size 20 of the hole may be obtained. The hole 20 communicates with a vertical passageway 22, the lower end of which constitutes a valve seat. The passage 22, when open, connects the hole 20 to a hole 23 or 23'. Desirably I 25 use the hole 23 (illustrated in Fig. 1) which opens into the mixing chamber 15 to receive explosive mixture therefrom; as that arrangement has some advantage. Instead of the hole 23 from the mixing chamber 15, I 30 may use the hole 23' (illustrated in Fig. 2) which opens to the atmosphere, so that when the passage 21 is open it connects the hole 20 to the atmosphere.

A valve 25 co-operates with the valve seat 35 at the lower end of the passage 22. This valve 25 is desirably a conical valve, formed at the upper end of a plunger 26. This plunger is movable vertically in a tube 27, which has its upper portion mounted in a tube-re- 40 ceiving opening 28 in the main body of the carburetor and its lower portion dipping into the float bowl 11 and extending nearly to the bottom of such float bowl. The plunger 26 desirably has its intermediate portion of 45 smaller size than the interior of the tube 27, for reduction of friction; but has its upper end 29 and its lower end 30 of proper size to have a sliding fit in said tube.

The effective size of the hole 23 or 23' is de- 50 sirable adjustable. To this end, for example, the upper end 31 of the tube 27 may be cut off obliquely, so that by turning the tube on its axis it is possible to adjust the effective size of such hole 23 or 23'. This adjustment, 55 however, is ordinarily made once for all, and the tube 27 is then fastened in adjusted position by a lock-screw 32, which desirably co-operates with a circumferential groove 33 in the tube to hold the tube at the proper height 60 as well as in the proper angular position.

The lower end of the tube 27 is closed by a screw-plug 35, so that the lower part of such tube serves as a dash-pot cylinder in which the lower end 30 of the plunger 26 recipro- 65 cates as a dash-pot piston. At about the level

of the fuel 10 in the float chamber 11, the tube 27 is provided with a lateral opening 36, by which the lower end of the tube is kept filled with fuel to serve as the dash-pot liquid. The tube has another lateral opening 37, at a point higher than the opening 36, to provide an air-bleed to make certain that no fuel will be drawn up through the tube 27 past the upper part of the plunger 26.

The lower end 30 of the piston 26 is provided with an upwardly opening check valve, so that the dash-pot formed by the lower ends of the plunger and tube will act to retard upward movement of the plunger but not to retard downward movement thereof. This check valve is desirably a ball 40 normally resting in a seat at the upper end of a hollow screw-plug 41 screwed into the bottom of the plunger 26, the ball when seated closing the opening 42 through such plug 41. The ball plays in a small chamber 43 provided in the lower end 30 of the plunger. The upper end of such chamber 43 has a lateral outlet 44 to the surface of the plunger at the smaller intermediate portion thereof and in prox- 90 imity to the opening 36 in the tube.

In operation, when the suction above the throttle disk 17 is below a certain value, (or the pressure is above a certain value), the plunger 26 drops in the tube 27, because the weight of such plunger overcomes such suction. The dropping of the plunger is rapid, because the ball valve 40 opens as the plunger descends, to permit fuel to pass from beneath the plunger out through the opening 42, the chamber 43, and the openings 44 and 36.

Whenever the suction above the throttle disk rises sufficiently high, (or the pressure falls sufficiently low,) however, thus over-coming the weight of the plunger 26, the plunger 26 rises. This rising is slow, because of the dash-pot action of the lower end 30 of the plunger in the lower end of the tube 27, for the ball 40 is on its seat in this up-ward movement and free passage of the dash-pot liquid is therefore prevented. Conse- 105 quently, it takes a definite time, of some length, for the plunger to make its full travel. When the plunger reaches the end of its up-ward movement, it engages the valve seat at the lower end of the passage 22, and thus shuts off the supply of explosive mixture or of air to the hole 20.

This effectively avoids stalling of the engine such as frequently occurs at the begin- 115 ning of a period of idling after a period of operation at low suction and low air velocity. During the operation at low suction and low air velocity, a considerable quantity of fuel has collected on the walls of the mixture pas-sage above the throttle, as well as on the throttle disk itself and its shaft. When the throttle is closed, and the vacuum above the 120 throttle is increased, this collected fuel is 130

added to the mixture, to produce a mixture which is too rich to explode in the engine. this is prevented by my invention; because when the throttle 17 is first closed the mixture above the throttle is prevented from becoming too rich, by additional air which comes in as such or as the air of normal explosive mixture through the by-pass passage or conduit provided by the hole 20, the 5 passageway 22, and the hole 23' or 23. The additional air thus admitted through the hole 20 into the space above the throttle keeps the mixture above the throttle sufficiently lean to ensure capacity of explosion in the engine, and the greater quantity of mixture reaching the engine keeps the engine speed slightly 10 higher. This additional supply of air from the mixing chamber, or from the atmosphere, continues for only a short time, while the 15 plunger 20 is rising, and is stopped when the valve 25 seats itself against the lower end of the passageway 22. This period of time, however, is sufficiently long to dispose of the accumulated fuel; as the valve 25 does not 20 seat itself until a sufficient period of time has elapsed for that. Thus during the beginning of an idling period, the idling is at higher than ordinary idling speed, by reason of the additional air which is admitted through the 25 hole 20; but this higher idling speed continues for only a short time, during which this collected fuel is used up, and then the valve 25 closes and the idling speed becomes normal. The time required for the valve 25 to 30 close may be varied by adjusting the tube 27 circumferentially.

This also serves to facilitate starting, especially when the hole 22 is supplied by the hole 23 from the mixing chamber 15 as illustrated in Fig. 1. It is found by experience that an engine starts more easily if the throttle is partly open. When the engine is at rest, the plunger 26 is down, so that even though the throttle 17 is closed explosive mixture may pass through the holes 23, 22, and 20 into the space above the throttle, to produce an effect equivalent to having the throttle partly open. This facilitates starting; but soon after the starting the suction developed 40 above the throttle 17 draws up the plunger 26, and shuts off the additional supply of explosive mixture admitted through the hole 20, and lets the engine operate at normal idling speed.

55 I claim as my invention:—

1. In combination, a carburetor mixing chamber into which air and fuel are supplied and from which a mixture-discharge passage leads, a throttle controlling said mixture-discharge passage, a conduit for admitting additional air to said mixture-discharge passage on the engine side of the throttle when the throttle is closed, and means for producing a delayed closing of said additional-air conduit following an increase above a pre-

determined value in the suction in said mixture-discharge passage on the engine side of said throttle.

2. In combination, a carburetor mixing chamber into which air and fuel are supplied and from which a mixture-discharge passage leads, a throttle controlling said mixture-discharge passage, a conduit for admitting additional mixture from said mixing chamber to said mixture-discharge passage on the engine side of the throttle when the throttle is closed, and means for producing a delayed closing of said additional-mixture conduit following an increase above a predetermined value in the suction in said mixture-discharge passage on the engine side of said throttle. 80

3. In combination, a carburetor mixing chamber into which air and fuel are supplied and from which a mixture-discharge passage leads, a throttle controlling said mixture-discharge passage, operating means for said throttle, and means for delaying the complete resultant decrease in the air supply to said mixture-discharge passage on the engine side of said throttle when said throttle-operating means is moved to cut down the quantity of the mixture discharge through said mixture-discharge passage. 90

4. In combination, a carburetor mixing chamber into which air and fuel are supplied and from which a mixture-discharge passage leads, a throttle controlling said mixture-discharge passage, operating means for said throttle, and means for delaying the complete resultant decrease in the mixture supply from said mixing chamber to said mixture-discharge passage on the engine side of said throttle when said throttle-operating means is moved to cut down the quantity of the mixture discharge through said mixture-discharge passage. 100

5. In combination, a carburetor mixing chamber into which air and fuel are supplied and from which a mixture-discharge passage leads, a throttle controlling said mixture-discharge passage, a conduit for admitting additional air into said mixture-discharge passage on the engine side of said throttle, a valve for closing said additional-air conduit, said valve being operable by engine suction and having a tendency to move to open position but being associated with said mixture-discharge passage so that it tends to move to close said additional-air conduit upon an increase to a predetermined value in the suction in said mixture-discharge passage on the engine side of the throttle, and retarding means for delaying the closing of said valve. 115

6. In combination, a carburetor mixing chamber into which air and fuel are supplied and from which a mixture-discharge passage leads, a throttle controlling said mixture-discharge passage, a conduit for admitting additional air into said mixture-discharge passage on the engine side of said throttle. 120

- and a valve for closing said additional-air conduit, said valve being operable by engine suction and having a tendency to move to open position but being associated with said mixture-discharge passage so that it tends to move to close said additional-air conduit upon an increase to a predetermined value in the suction in said mixture-discharge passage on the engine side of the throttle.
7. In combination, a carburetor mixing chamber into which air and fuel are supplied and from which a mixture-discharge passage leads, a throttle controlling said mixture-discharge passage, a fuel chamber containing fuel to be supplied to said mixing chamber, a conduit for admitting additional air into said mixture-discharge passage on the engine side of the throttle, a valve for controlling said additional-air conduit, a plunger associated with said valve to operate it, said plunger having a tendency to move to a position to open said valve but being subject to the suction in said mixture-discharge passage so that such suction tends to move it to close said valve, and a dash-pot for retarding the movement of said plunger in the direction to close said valve, said dash-pot being a liquid dash-pot arranged to receive its liquid from said fuel chamber.
8. In combination, a carburetor mixing chamber into which air and fuel are supplied and from which a mixture-discharge passage leads, a throttle controlling said mixture-discharge passage, a conduit for admitting additional air into said mixture-discharge passage on the engine side of the throttle, a valve for controlling said additional-air conduit, a plunger associated with said valve to operate it, said plunger having a tendency to move to a position to open said valve but being subject to the suction in said mixture-discharge passage so that such suction tends to move it to close said valve, and a dash-pot for retarding the movement of said plunger in the direction to close said valve.

In witness whereof, I have hereunto set my hand at Indianapolis, Indiana, this 11th day of March, A. D. one thousand nine hundred and twenty-five.

HOWARD W. LINKERT.
